UNITED STATES PATENT OFFICE.

JOHN D. RIPSON, OF WEST TORONTO, ONTARIO, CANADA.

WATER-WHEEL.

1,067,064.

Specification of Letters Patent.

Patented July 8, 1913.

Application filed July 11, 1912. Serial No. 708,829.

To all whom it may concern:

Be it known that I, JOHN D. RIPSON, a citizen of the United States, residing at West Toronto, in the county of York, Ontario, Canada, have invented certain new and useful Improvements in Water-Wheels, of which the following is a specification.

The object of this invention is to provide a water wheel or current power machine 10 that can be supported from the bank of a stream, the blades of which are immersed in water, the wheel being driven by the ordinary current of the water in the river or creek in which the blades are immersed.

Another object of my invention is to construct the wheel so that it is supported from 15 a bearing on but one side thereof.

Another object of my invention is to make the blades on the wheel adjustable so that 20 they can be raised or lowered according to the stage of the water in the river or creek, without shifting the axis of the wheel or without materially changing the diameter of the wheel.

Another object of my invention is to provide gearing by which the power of the wheel is transmitted directly to the machinery 25 on shore that is to be driven thereby.

Another object of my invention is to mount the wheel so that it may be readily 30 taken from the water so as to stop the driving thereof.

These and other objects of my invention will be fully illustrated in the drawings, 35 described in the specification and pointed out in the claims at the end thereof.

In the accompanying drawings, Figure 1 is a sectional elevation of my wheel as it will appear mounted upon the bank of a stream. 40 Fig. 2 is a top plan view of my wheel with all but two of the blades or flanges omitted therefrom. Fig. 3 is a perspective view of the housing or box in which the transmission gear is contained. Fig. 4 is a front 45 view of one of the blades or flanges of the wheel. Fig. 5 is a section on the line 5^x—5^x in Fig. 4. Fig. 6 is a section on the line 6^x—6^x in Fig. 1. Fig. 7 is a perspective view partly broken away of a modified form 50 of my invention.

In the accompanying drawings like reference numerals refer to like parts.

In the drawings reference numeral 1 in-

dicates the bank of a stream and 2 indicates the water in the stream.

3 is the concrete or masonry base which is first laid for the mounting of the wheel. On top of this is placed the base plate 4 of the machine which is fastened to the concrete base by the bolts 5, 6, 7 and 8. On 60 top of the base plate 4 is the shell 9 which together with the base plate 4 constitutes a housing for the beveled gear 10. The shell 9 is fastened to the base 4 by studs which pass up through the base from below, 65 the two parts being connected together before the base is fastened in place by the bolts 5, 6, 7 and 8.

The beveled gear 10 is mounted upon a shaft 11 to which it is keyed and which rotates therewith. The base plate 4 is finished with a boss 12 which forms a bearing for the beveled gear 10 which takes up the vertical thrust thereof, and the shell 9 is provided with a journal box 13 at the top there- 70 of in which the top of the shaft 11 is free to rotate. On top of the shell 9 are provided the lugs 14, 15, 16 and 17 in which is pivotally mounted a plate 18, the lugs being shown in Fig. 3 and the plate being shown 80 in section in Fig. 1. On this plate is a segmental gear 19, which gear extends down through the opening 20 provided in the shell 9 therefor.

Mounted in the shell 9 is the shaft or stem 85 21 which extends through the side of the shell and has upon the outer end thereof the operating lever 22 and upon the inner end the pinion or gear 23. This pinion meshes with a segmental gear 19 and by this pinion 90 23 the segmental gear 19 is operated, so that the plate 18 can be tilted from the angular position shown in Fig. 1 to a horizontal position corresponding with the top of the shell 9. The outline of this plate 18 is 95 shown in dotted lines in Fig. 2.

Mounted in the plate 18 and stationary therewith is the shaft 24, which shaft has a flange 25 at the bottom thereof by which it is fastened to the plate 18 by means of the 100 screws 26 and 27. Mounted to rotate upon this shaft is the crown gear 28, which gear has the teeth 29 thereon which mesh with similar teeth upon the beveled gear 10 by which the motion of the wheel is transmitted to the beveled gear 10. The plate 18 and

the gear 28 are each provided with grooves 30 and 31 that form a ball race in which a series of balls are placed to form a ball bearing between the gear 28 which revolves over the plate 18 which is stationary.

The gear 28 revolves around the shaft 24 and is held in place thereon and in mesh with the gear 10 by means of a collar 32, which collar may be fastened upon the shaft 10 with a set screw or in any other desired manner. At the top of the shaft 24 is placed a collar 33 which is fastened to the shaft by means of a pin 34. Above the collar 33 on the shaft 24, and mounted to rotate around the shaft 24, is the wheel 35. This wheel has a circular groove 36 therein and the collar 33 has a similar groove thereon, which grooves constitute between them a ball race in which a string of balls is placed that constitutes a thrust ball bearing between the wheel 35 and the collar 33.

Above the wheel 35 is provided a collar 37 which is keyed to the shaft 24 and holds the wheel 35 in place. Cut in the back of the gear 28 are the radial slots 38, 38, twenty-two of which are shown in Fig. 2, although it is obvious that these may be of any desired number. These radial slots are spaced evenly apart with the same angular distance between them. One of these slots is shown in Fig. 6. On each side of the radial slots are bolted the flanges or braces 39 and 40. Pivotaly mounted between these flanges or braces and the pins 41 are the arms 42. On the end of these arms are provided the blades 43, one of which is shown complete in Fig. 4. The arm 42 is divided, one part of which extends along and is riveted to the upper edge of the blade 43, and the other part of which extends down and is riveted along the end and the bottom of the blade, strengthening the blade and making it more rigid. These blades at the outer end are bent up at an angle and at the bottom are bent up with a flange 44, so that the whole when finished forms a bucket or cup against which the water positively engages in order to force the rotation of the wheel to which it is attached. Two of these blades 43 are shown in top plan view in Fig. 2. On the back of each blade is mounted a brace 45 which extends rearwardly and makes contact with the succeeding blade, by which the blades tend to hold each other equally in position. The braces 45 are only fastened to one blade and maintain only sliding contact with the blade at the rear. This permits this blade to rise and fall separately from the rest, as obstructions in the stream may necessitate, such as floating ice or wood, etc.

Fastened to the wheel 35 are the pulleys 46 over which extend the cables 47, each of which cables is fastened at the outer end to a lug 48 on the blade 43. The cable passes over the pulley 46 and is connected to a

windlass 47^A upon which it is wound up. This windlass has thereon a pinion or gear 48^A. Both the windlass and the pinion are mounted upon a shaft 49, which shaft is mounted to rotate between flanges 50 and 51. Also mounted to rotate between the flanges 50 and 51 is the crank shaft 52 having the pinion 53 thereon, which pinion meshes with the pinion 48, so that the pinion 48 and windlass 47 can be turned by turning the crank 54. A pawl 55 and ratchet 56 are furnished on each of these crank shafts to prevent backward rotation thereof. By turning the crank 54 the cable 47 may be drawn down and the blade 43 connected thereto may be drawn up to any position desired. Each of the blades may be drawn up in the same way by the operation of its particular crank, windlass and cable, and the blades should be drawn up to a uniform position. The blades should be immersed so that the water comes just to the top of the blade. As the water in the stream rises the blades can be elevated to any desired height.

The flanges 39 and 40 afford a strong and sufficient bearing to take up the leverage of the arm 42 and cause the wheel to rotate uniformly therewith, and the cables 47 are amply strong enough to support the blades 43 in any position in which they may be placed while the wheel is rotating, due to the flow of the current.

Mounted upon the concrete base 4 is the upright 57. Journaled in this upright and in the back of the housing 9 is the shaft 58. The back of the housing is reinforced by the angle 59 which furnishes additional bearing surface for the shaft 58. Keyed to the shaft 58 are the beveled gear 60 and the pulley 61. The beveled gear 60 meshes with the beveled gear 10 and is driven thereby. A belt may be driven by the pulley 61 and applied to any machine or gearing on which the power is intended to be used.

Instead of the pulleys 46 and cables 47, tie rods connecting between the blades 43 and the wheel 35 may be used, which tie rods may include turn buckles by which the blades 43 may be raised and lowered as desired.

The operation of my machine is as follows: After the parts are placed in position as above described, the plate 18 and beveled gear 28 may be tilted to the position shown in Fig. 1 by the operation of the lever 22 and pinion 23. The blades may be placed at the desired height with reference to the level of the water in the stream by raising or lowering on the cables 47. The flow of the water in the stream will carry the blades 43 therewith and cause the beveled gear 28 to rotate. This in turn will communicate its power to the beveled gear 10, which in turn will communicate its power to 130

the beveled gear 60, driving the shaft 58 on the pulley 61.

If it is desired the blades 43 can be drawn part way out of the water, which will vary 5 the speed of and the power developed by the wheel.

It will be seen by the foregoing description 10 on the other side are elevated above the bank of the stream and that the water wheel is supported entirely from one bank of the stream and that no obstruction need be placed in the bed of the stream that will 15 interfere with the flow of the water.

It will also be seen from the sectional view 20 in Fig. 1 that the machine is mounted so that the base and housing partially overhang the water, so that the blades will have water of sufficient depth at which to operate. The angular position of the wheel causes the 25 blades as they leave the water to pass up over the land and enter the water from the upside of the stream.

In Fig. 7 I have shown a modified form 30 of my invention, the purpose of which is to provide for the use of my improved water wheel on the banks of streams where the banks are high and steep and where there is great fluctuation in the stage of the water. In this modification I provide a sill 70 on each end of which are mounted inclines 71 having runners or guides 72 and 73 therein. In this instance the shell or frame of the 35 machine is not anchored to the base but is mounted to run up and down upon these guideways. For this purpose I provide the shell with lugs or guides 74, 75, 76 and 77 on each side thereof, which guides engage 40 with the guides on the stationary frame and hold the shell in any position in which it may be placed with relation to the frame. On top of the shell I provide the lugs 78 and 79 to which are attached cables 80 and 81 45 which pass up over the pulleys 83 and 83 and down over the drum of the windlass 84. By turning the windlass the shell may be raised up or down and suspended in any desired elevation. The water wheel will be 50 mounted upon the inclined face of the drum with its blades extending down into the water at the lower edge, as is illustrated in the other figures of the drawings. When this modification is used the water wheel as 55 a whole will be raised and it will not be necessary to rock the wheel by the use of the lever 22 and the parts associated therewith.

Having thus described my invention, 60 what I claim as new and patentable is as follows.

1. The combination in a water wheel of a wheel having blades thereon distributed around the periphery thereof, said wheel 65 being mounted at an incline to the water,

a shaft for supporting said wheel, around which shaft said wheel rotates, said shaft being inclined from the vertical, means for tilting said shaft to a vertical position and carrying the wheel therewith, a beveled gear mounted on an upright axis a beveled gear 70 upon said shaft, said gears being in mesh with each other when said wheel is in its inclined position, said gears being arranged to permit adjustment of the tilting gear without disturbing the gear on the upright axis. 75

2. The combination in a water wheel of a base plate, a housing therefor, a vertical shaft mounted between said base plate and said housing, a beveled gear keyed to and mounted to rotate with said shaft, said housing being inclined on one side, a plate pivotally mounted on said housing and adapted to be tilted between the horizontal top of said housing and the inclined side thereof, a shaft 80 mounted on said plate a beveled gear provided with blades adapted to rotate around said shaft, said gears being adapted to mesh with each other when the plate is in an inclined position. 85

3. The combination in a water wheel of a base plate, a housing therefor, a vertical shaft mounted between said base plate and said housing, a beveled gear keyed to and mounted to rotate with said shaft, said housing being inclined on one side, a plate pivotally mounted on said housing and adapted to be tilted between the horizontal top of said housing and the inclined side thereof, a shaft mounted on said plate, a beveled gear adapted to rotate around said shaft, a ball bearing provided between said beveled gear and said plate. 90 95

4. The combination in a water wheel of a base plate, a housing therefor, a vertical shaft mounted between said base plate and said housing, a beveled gear keyed to and mounted to rotate with said shaft, said housing being inclined on one side, a plate pivotally mounted on said housing and adapted to be tilted between the horizontal top of said housing and the inclined side thereof, a shaft mounted on said plate, a beveled gear adapted to rotate around said shaft, a ball bearing provided between said beveled gear and said plate, said beveled gear being grooved on the back thereof, flanges on either side of said groove, blades pivotally mounted between said flanges. 100 105 110 115

5. The combination in a water wheel of a base plate, a housing therefor, a vertical shaft mounted between said base plate and said housing, a beveled gear keyed to and mounted to rotate with said shaft, said housing being inclined on one side, a plate pivotally mounted on said housing and adapted to be tilted between the horizontal top of said housing and the inclined side thereof, a shaft mounted on said plate, a beveled gear 120 adapted to rotate around said shaft, a ball 125 130

bearing provided between said beveled gear and said plate, said beveled gear being grooved on the back thereof, flanges on either side of said groove, blades pivotally mounted between said flanges, means carried on said wheel for raising or lowering said blades.

6. The combination in a water wheel of a base plate, a housing therefor, a vertical shaft mounted between said base plate and said housing, a beveled gear keyed to and mounted to rotate with said shaft, said housing being inclined on one side, a plate pivotally mounted on said housing and adapted to be tilted between the horizontal top of said housing and the inclined side thereof, a shaft mounted on said plate, a beveled gear adapted to rotate around said shaft, a ball bearing provided between said beveled gear and said plate, said beveled gear being grooved on the back thereof, flanges on either side of said groove, blades pivotally mounted between said flanges, a windlass for each of said blades mounted on said beveled gear, pulleys supported above said beveled gear, cable passing between said blades and over said pulleys to said windlass by which said blades may be raised or lowered.

17. In a water wheel the combination of a disk mounted to rotate on a shaft pitched at an angle to the horizontal, radial arms pivoted on said disk, blades fastened to said arms, each of said blades having a brace mounted thereon and extending forwardly therefrom to engage the preceding blade.

8. In a water wheel, the combination of a hollow base, a shaft mounted to rock on said base, a water wheel having blades thereon mounted to rotate on said shaft, said shaft being capable of standing vertical with the wheel substantially horizontal and capable of being inclined with one side of the wheel depressed and the other side elevated,

40 a gear on the wheel adapted to rock and rotate therewith, a gear in the base adapted to rotate therein in a fixed position, said gear on the wheel meshing with and driving the gear in the base when the wheel is in an inclined position.

45 9. The combination of a water wheel, an axis therefor supported on one side, said axis being capable of tilting with its support from an upright to an inclined position,

55 blades on said water wheel being adapted to be raised or lowered with reference to said support, said blades engaging with the water on one side of said wheel when the shaft is inclined and driving said wheel, a gear fastened to said wheel and adapted to rotate therewith, a gear mounted below said axis and independent thereof with which said first named gear is adapted to mesh when the wheel is in its inclined position, said

60 65 wheel being adapted to transmit its power

through said gears the same being arranged to permit adjustment of the tilting gear without disturbing the gear on the upright axis.

10. The combination in a water wheel, of a hollow base, a gear mounted to rotate therein, said wheel having blades thereon supported above said gear and adapted to rotate over it, a gear on said water wheel, said water wheel being adapted to tilt to engage its blades on one side with the water and bring said gears into mesh with each other.

11. In a water wheel, the combination of a base, a gear mounted to rotate therein, a water wheel having blades thereon supported above said gear and adapted to rotate over it, a gear on said water wheel, said water wheel being adapted to tilt to engage its blades on one side with the water and bring said gears into mesh with each other, means to raise and lower the blades of said wheel with reference to said gear.

12. In a water wheel, the combination of a base having two surfaces thereon which are inclined at an angle to each other, a shaft pivotally mounted on said base at the junction of said surfaces, a water wheel adapted to rotate around said shaft, said wheel having blades distributed around the periphery thereof, said wheel and said shaft being capable of tilting to bring the wheel into contact with either of said surfaces.

13. The combination in a water wheel of a hollow base, a gear mounted to rotate therein on an axis, a wheel having blades thereon supported above said gear with a fixed support interposed between said gear and said wheel, said wheel being adapted to rotate over the gear, a gear on the water wheel moving therewith, said water wheel being adapted to tilt to engage its blades on one side of the water and bring said gears into mesh with each other.

14. In a water wheel the combination of a wheel having a beveled gear thereon, a shaft therefor, said wheel revolving around the bottom of the shaft, a support for said shaft on which said shaft is adapted to rock toward and from the vertical, a beveled gear adapted to rotate under said support, said wheel and its shaft being capable of tilting to bring the two beveled gears into mesh with each other.

15. In a water wheel, the combination of a support, a plate adapted to rock on said support, a quadrant connected to said plate, a pinion mounted upon the support meshing with said quadrant for the purpose of rocking said plate, a shaft mounted on said plate and rocking therewith, a wheel adapted to revolve around said shaft and rock with the shaft and plate.

16. In a water wheel, the combination of a support, a plate adapted to rock on said

support, a quadrant connected to said plate, a pinion mounted upon the support meshing with said quadrant for the purpose of rocking said plate, a shaft mounted on said plate and rocking therewith, a wheel adapted to revolve around said shaft and rock with the shaft and plate, a beveled gear on said wheel above the support, a beveled gear mounted on a shaft below the support, said pinion and quadrant being operable to move the upper gear into and out of mesh with the lower gear.

5 In testimony whereof I affix my signature in presence of two witnesses.

JOHN D. RIPSON.
